UNITED STATES PATENT OFFICE

HARRY L. KISTLER AND PETER J. TROMPETER, JR., OF PERU, ILLINOIS

SUBGRADE PLANER

Application filed September 27, 1929. Serial No. 395,606.

The present invention relates to road building machines, and more particularly to a planing attachment for subgrades of roads preparatory to the spreading of surfacing materials.

An object of the present invention is to provide an attachment for road building machines, such as paving machines of the present day type utilizing a loading skip which extends forwardly from the machine to receive the road building material to be mixed in the machine, and aims to utilize the space between the loading skip and the frame of the machine to accommodate the improved planer or scraper.

The common paving practice at the present time is to transport the paving material to the mixer in trucks and this operation frequently forms ruts, or otherwise disturbs the prepared subgrade to such an extent that a mechanical means of relevelling the subgrade is generally employed to minimize the amount of handwork necessary.

With planers or scrapers of the present known type the purpose is frequently defeated when hard or compact material is encountered, as the blades of the planer or scraper are set at right angles to the direction of the travel of the planer and the tendency in such cases is to ride over such spots, leaving considerable handwork still to be done.

It is therefore another object of this invention to provide a planer of such construction and to so mount the blades therein that these blades will effectively cut or slice off projections of the material of the subgrade and work the loose material crosswise of the road so that the material may properly seat in depressions or the like which are formed beyond the ruts or the breaking up of large lumps of the subgrade material. In carrying out this purpose the excess loosened material is delivered at the opposite outer sides of the traction devices or treads of the road building machine where it may be readily removed or disposed of with very slight manual labor.

Another object of the invention is to provide a planer adapted to ride and rest upon the side rails which define the lateral edges

of the road structure, and a planer which has a frame capable of extension and retraction to adapt the planer to roads of different widths.

The invention further aims at the provision of an improved coupling and pressure means which is capable of adjustment and capable of universal movement to adapt the planer to road mixers of various types and dimensions and which is adapted to exert a suitable downward pressure upon the planer to maintain it in position and assist the blades of the planer in cutting through and leveling off the subgrade.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a side elevation of a road building machine, partly broken away and showing the loading skip in lowered position and with the planer of this invention connected to the machine.

Figure 2 is a top plan view of the same.

Figure 3 is an enlarged fragmentary section on the line 3-3 of Figure 2 taken through a portion of the planer showing the mounting of one of the pressure and lifting elements therefor.

Figure 4 is a transverse section through the central portion of the planer taken substantially on the line 4-4 of Figure 2.

Figure 5 is an enlarged fragmentary section taken through a portion of the planer frame and showing one of the adjustable connections for attaching the planer to a road building machine.

Figure 6 is an enlarged transverse section taken through one of the planer blades and its support.

Figure 7 is a fragmentary front elevation of the same, and

Figure 8 is an enlarged transverse section taken longitudinally through one end of the planer frame, showing the adjustable extensions connected thereto.

Referring to the drawings, 15 designates the body of a road building machine, which may be a material mixer with its attendant parts of any suitable construction, and is shown diagrammatically in the drawings. The road machine 15 is provided with propelling wheels 16 which are disposed in longitudinal alignment on shafts 17 and 18, the wheels 16 carrying a traction belt 18 having treads 19, providing a traction support for the machine. At the forward end, the road machine 15, is provided with the usual loading skip 20 which projects downwardly from the upper part of the machine and is adapted to receive the various materials which are dumped into the skip, the materials adapted to be fed to the mixture when the loading skip is raised. From Figure 1 particularly it will be noted that there is a space between the loading skip 20 and the forward end of the main body portion of the road machine 15. The planer of the present invention is constructed and proportioned to fit in this space so that the space may be utilized and the sub-grade operated upon immediately prior to the passage of the road machine 15 thereover.

The planer of this invention comprises a transversely extending frame composed of front and rear beams, 21 and 22. The beams 21 and 22 may comprise a built up structure, such as shown in Figures 4, 5 and 8 and wherein the main body part is composed of a pair of spaced channel irons 25 with their web portions confronting one another and 35 with their flanges extending in opposite directions, and top and bottom plates 24 connected to the flanges of the channel irons as by rivets 24'.

The front and rear beams 21 and 22 are secured in parallel spaced relation by cross pieces 26 of suitable beam construction with gussets riveted or otherwise suitably secured to the beams 21 and 22 to form therewith a substantially rectangular elongated frame. At each end the planer is provided with an extension 27 comprising a body part or beam 27' which is arranged in parallel relation with respect to the end beams 26 of the main frame and arms 28, in the example shown comprising channel irons 28' arranged with their web portions abutting in face engagement and secured together by rivets 23, slidably disposed within the opposite end portions of the beams 21 and 22 and which are 55 locked in adjusted position by bolts 29 or the like, as shown particularly in Figure 8.

These extension frames 27 carry flanged wheels 30 adapted to engage and ride upon the upper edges of the side strips or rails used for confining the road material within the width of the roadway, these strips or rails being shown at 31 in Figures 1 and 2.

The main frame is provided at its intermediate portion and upon its forward beam 33 21 with a V-shape planer or cutter blade 32

which is arranged with its angle or point directed forwardly and with its side portions secured by angle plates 33 or the like across the under side of the beam 21. This planer blade 32 may be provided at its rear end portion with a cross brace 34 suitably secured to the blade 32 by gussets or the like as shown so as to brace the blade 32 against collapsing.

The rear beam 22 of the frame is provided with a pair of diagonally extending planer or scraper blades 35 which are secured by attaching plates 36 or the like across the under side of the beam 22 with the blades 35 offset inwardly toward each other a sufficient distance from the rear ends of the blade 32 to provide an overlap so that the transverse width of the subgrade will be completely traversed during the forward movement of the planer.

From Figure 2 it will be noted that the blades 35 are of sufficient length to terminate beyond the treads 19 of the road building machine so that material which is loosened or cut off from the subgrade, and which is not moved into ruts or depressions in the sub-grade, is rolled and carried beyond the sides of the machine so that the material may be easily and conveniently handled.

At each end of the machine the forward beam 21 may be provided with a short scraper blade 37 secured diagonally across the under side of the beam 21, inclined inwardly and rearwardly, disposed at substantially right angles to the blades 32 and 35, and arranged to slightly overlap the rear end portions of the blades 35. Outwardly of the short blade 37 the frame is provided with relatively long planer or scraper blades 38 which extend across the under side of the beams 21 and 22 and each of which is disposed preferably in parallel relation to the adjacent short blade 37; there is one long blade 38 at each end of the planer frame.

In order to completely cover the width of the roadway when the extensions 27 are employed, each extension is provided with a short blade 39 which is secured across the under side of the forward arm 28 thereof and which is preferably braced at its rear end by a diagonal brace 40 which extends between the blade 39 and the rear end of the extension 27. The blade 37 is disposed preferably in parallelism with the adjacent long blade 38 and is adapted to overlap the same to an extent dependant upon the adjustment of the extension 27.

As shown in the drawings, particularly Figure 3, each intermediate brace 26 may be provided with an up-standing stud 41 having a coupling ring 42 adapted to be connected with a suitable hoist to raise and lower the planer in removing and positioning the same with respect to the road being built.

The planer is also provided with a pair of levers 43, one for each stud 41 and each is

preferably pivotally mounted intermediate its ends upon a bolt 44 which is carried in the upper end of its respective stud 41. The lever 43 extends through the ring 42 and at 5 its rear end engages beneath a cross beam 45 which is secured to the forward end of the road machine 15, the levers 43 extending in divergent relation from the forward end of the road machine 15 and across the top of the 10 planer frame and beyond the latter. Where it is desired to exert additional pressure upon the planer frame, such pressure may be applied to the forward ends of the levers 43 so as to urge the planer frame downwardly and thus hold the wheels 30 to the 15 rails 31 and maintain the scraper blades in the desired elevation with respect to the subgrade.

As a means of carrying and propulsion for the planer, the latter is provided with a pair of push bars 46 which may be of hollow tubular construction externally threaded at opposite ends and adjustably receiving thereon fork couplings 47 having apertured 20 arms, as shown in Figure 5, which pivotally engage pins 48 projecting from a disc 49 which is detachably mounted on a stud 50 carrying a nut 51 for holding the disc 49 thereto. The tubular body part of the push bar 46 has threaded engagement in the outer 25 end 47 and is locked thereto in adjusted position by an adjusting nut 52 so that the push bar 46 may be adjusted as to length within practical limits. The disc 49 is adapted to 30 turn freely upon the stud 50 and admit of the swinging adjustment of the push bar 46. The opposite end of the push bar 46 is connected in a similar manner to the rear shaft 17 of the road machine so that the propulsion 35 of the planer is effected through the push bars 46 and the opposite ends of the shaft 17.

In order to maintain a definite relation between the road machine 15 and the planer, coupling bars 53 of like construction to the 40 pusher bars 46 are disposed between the opposite ends of the forward axle 18 of the road machine and the outer end portions of the planer frame.

These coupling bars 53 are also adjustable 45 as to length and permitted to swing so that the road machine may rise and fall with respect to the planer without disturbing the adjustment of the latter.

Each of the scraper or planer blades used 50 is of the type shown in Figure 6 wherein the blade 38' is transversely curved with its lower cutting edge turned forwardly to a slight extent so as to produce a cutting or shearing action rather than a mere scraping or leveling action. Of course the loose particles which pile up against the forward side 55 of the blade 38' are rolled and worked along the blade to the rear end thereof. It will be noted that all of the blades are so disposed 60 as to provide an open throat 54 at the rear of

the planer and at each side of the path of travel of the road machine 15. Each blade 38' is secured at its upper end to the depending flange of an angle bar 55 which forms the upper attaching portion of the blade for direct contact with the beams 21 and 22 and the other parts of the frame. Bolts 56 engage through the bar 55 and the blade 38' for holding the latter to the bar, and the blade 38' may have vertical slots 57 therein for receiving the bolts 56 and to permit vertical adjustment of the blade 38'.

In operation, as the road machine 15 advances the loading skip 20 is used in the ordinary manner and the sub-grade in advance of the loading skip 20 is rutted and otherwise disturbed by the passage of trucks or other vehicles or devices used in supplying material to the machine. The planer is advanced by the machine immediately behind the loading skip 20 and traverses the entire width of the roadway, cutting off projecting portions of material and rolling the loose material back and forth between the various angularly disposed blades until the material is deposited and worked into depressions or crevices in the surface of the subgrade, or until the excess loose material is finally delivered in a hill extending along the opposite sides of the road machine 15. It will be noted that the short blades 37 are disposed in longitudinal alignment with the delivery throat 54 of the machine so that the entire width of the roadway is subjected to the action of the planer.

Where additional weight is required, such as when operating in extra heavy or hard material, the weight may be applied by hand or otherwise to the outer ends of the levers 43 so that the latter may exert the applied pressure upon the intermediate portions of the frame of the planer. As the levers 43 are pivoted upon the bolts 44 of the planer frame, the pressure is evenly distributed throughout the width and length of the planer frame and the pressure is thus maintained evenly on all of the scraper blades used.

The pusher bars 46 directly propel the planer on its wheels 30 while the coupling bars 53 hold the planer in proper transverse alignment with the road machine and these 115 bars 46 and 53 permit of relatively vertical movements of the planer and the road machine during operation and adjustment of the same.

It is of course understood that various 120 changes and modifications may be made in the details of construction and design of this invention without departing from the spirit thereof, such changes and modifications being restricted only by the scope of the following claims.

What is claimed is:

1. In combination with a road building machine, a subgrade planer comprising a transverse frame positioned in front of the 125

forward end of the road machine, bars pivotally carried by the frame extending upwardly and in rearwardly converging relation therefrom and pivotally attached to the machine for advancing the frame ahead of the machine, means on the opposite ends of the frame for travelling on the spaced forms at opposite sides of the road, and planer blades carried by the frame and extending downwardly therefrom for engagement with the subgrade to cut and level the same.

2. In combination with a road building machine, a subgrade planer comprising an elongated frame positioned across the front of the road machine, adjustable extensions mounted on the opposite ends of the frame, rollers carried by the extensions, said rollers adapted to engage upon the forms at opposite sides of the road, pusher connections between the frame and the road machine, certain of said connections extending downwardly from the road machine to the frame for urging the latter downwardly against the subsurface, groups of planer blades arranged at transverse angles across the under side of the frame and said extensions and adapted for contact with the surface of the subgrade for cutting projections therefrom and spreading said projections laterally over the roadway to fill in depressions occurring therein, said planer blades arranged in groups and with delivery throats at opposite sides of the road machine for depositing surplus loose material in hills along the opposite sides of the machine, and supplemental pressure means mounted on the forward end of the machine and extending over said frame for increasing downward pressure thereon.

3. In combination with a road building machine, a subgrade planer comprising a frame, a plurality of planer blades mounted in angular relation with respect to the frame and to one another across the under side of the frame, means for supporting the opposite ends of the frame with the planer blades in contact with the subgrade, adjustable universal connections between the frame and the forward end of the road making machine, and pressure levers operatively engaging said road machine and planer for urging the frame downwardly to hold the planer blades in contact with the subgrade.

4. A subgrade planer comprising an elongated frame adapted for positioning in front of a road making machine thereof, pusher connections carried by the frame adapted for connection with the road making machine and extending downwardly therefrom to

urge the machine into contact with the subgrade, a V-shape planer blade mounted across the under side of the frame intermediate the ends thereof and with the apex foremost, a second pair of spaced planer blades offset inwardly from the ends of the V-shape blade and disposed in substantially parallel relation thereto for catching loose material from the V-shape blade and carrying the material across the roadway to the opposite sides of the road machine, and other planer blades carried upon the opposite end portions of the frame and arranged at substantially right angles to the first-named blades and having their points of discharge beyond the opposite sides of the road machine.

5. A subgrade planer comprising a frame, adjustable extensions mounted on the opposite ends of the frame, means on said extensions adapted to traverse the forms at the opposite sides of the subgrade, angularly disposed planer blades secured across the under side of the frame, and planer blades carried by the extensions and arranged in overlapping relation with respect to the adjacent planer blades in the frame for co-operation therewith in covering the entire width of the subgrade.

6. In combination with a road building machine, a subgrade planer comprising a transverse frame positioned in front of the forward end of the machine, bars pivotally carried by the frame extending upwardly and in rearwardly converging relation therefrom and pivotally attached to the machine for advancing the frame ahead of the machine, and planer blades carried by the frame and extending downwardly therefrom for engagement with the subgrade to cut and level the same.

7. In combination with a road building machine, a subgrade planer comprising a transverse frame positioned in front of the forward end of the road machine, bars pivotally carried by the frame extending upwardly and in rearwardly converging relation therefrom and pivotally attached to the machine for advancing the frame ahead of the machine, planer blades carried by the frame and extending downwardly therefrom for engagement with the subgrade to cut and level the same, and weight levers in diverging relation from the forward end portion of the road building machine and operatively connected to the same and to the planer to aid in holding the latter down upon the subgrade.
